SOLVENT DEWAXING PROCESS

Oldrich S. Pokorny, Sarnia, Ontario, Canada, assignor to Standard Oil Development Company, a corporation of Delaware

Application November 19, 1938, Serial No. 241,327

3 Claims. (Cl. 196—18)

The present invention relates to the dewaxing of petroleum oils. The invention is particularly directed to an improved process of precipitating waxy constituents from the oil. The invention especially relates to a process in which a waxy distillate is blended with a suitable dewaxing solvent, the mixture heated to secure complete miscibility of the oil, the waxy constituents and solvent, and then shock or rapidly chilled through an initial cooling stage, slowly chilled through an intermediate stage and then rapidly chilled through the final stage.

It is well known in the art to dewax waxy petroleum oils by various procedures. A usual process is to take a relatively wide waxy distillate cut containing lighter boiling hydrocarbons and to chill to a temperature at which the waxy constituents precipitate. The lighter boiling hydrocarbons serve as diluents and facilitate subsequent filtering of the precipitated waxy constituents. The precipitated waxy constituents may also be separated by sedimentation, centrifuging and the like. Another procedure is to use dewaxing solvents or solvent mixtures of the class which have a preferential selectivity for non-waxy constituents or tend to precipitate the waxy constituents from the oil. It is also known to add other substances such as dewaxing and filtering aids and the like.

The waxy distillate is chilled in any suitable manner in order to lower the temperature to a point at which the waxy constituents precipitate. Following this procedure the waxy constituents are separated from the dewaxed oil by sedimentation, filtering or other means. In these processes it is known that the rate at which the chilled mixture may be subsequently filtered is a function, to a large extent, of the type of wax crystalline structure secured. It is also known that a desirable wax crystalline structure will be secured if the rate of chilling is controlled so that the temperature is lowered at a relatively low rate. By operating in this manner, filtering rates can be materially increased and the capacity of the filtering equipment substantially increased. This process, however, is not entirely satisfactory since in order to secure a desirable wax crystalline structure the time necessary to cool from the miscibility temperature to the dewaxing temperature is unduly long. This factor is of a critical nature when it is considered that in order to successfully operate a commercial process it is necessary that the maximum capacity of the equipment be secured. Thus, for example, if the cooling time be doubled, the ca-

pacity of the equipment would be halved which would materially increase the investment necessary and depreciation charges of the operation.

I have now discovered a process by which it is possible to chill a waxy distillate in a minimum of time and to secure a wax crystalline structure which will give subsequent maximum filtering rates. Thus, by my process overall efficiency of the chillers and the filters is secured. I have discovered that a critical range exists in the wax crystallization curve insofar as the wax crystallization structure affects subsequent filtering rates. In view of this discovery I regulate my process to secure optimum crystalline structure over the critical range and after passing through this range I operate in a manner to secure the maximum cooling rate. I have found that the filtering rates are almost a direct function of the character of the crystalline structure of the relatively high melting point waxes and that the wax crystalline structures of the relatively low melting point waxes do not adversely affect the filtering rates either when chilled slowly or rapidly. As the temperature of the solution drops, the relatively high melting point waxes are precipitated. As the temperature is further lowered, progressively lower melting point waxes are precipitated. The waxes that precipitate out at a temperature of about +35° F. and lower apparently do not form deleterious crystalline structures which will affect the filtering rate, but the crystals formed in the range from about +35° to +95° F. will adversely affect the rate, provided care is not used to secure the desired crystalline structure.

My process may be readily understood by reference to the attached diagrammatical flow plan showing one modification of the invention. Waxy distillate is introduced into chiller 1 by means of feed line 2. A suitable dewaxing solvent is mixed with the waxy distillate and introduced into feed line 2 by means of line 3. The waxy distillate is usually heated in heater 5 to a temperature at which complete miscibility occurs between the oil, the waxy constituents and the dewaxing solvent. The diluted waxy distillate is then passed to chiller 1 where the temperature is lowered through an initial stage either by direct or indirect cooling. For example, if the dewaxing solvent comprises propane, sufficient propane is allowed to evaporate to secure rapid chilling through this range. The propane is removed by means of line 6. The partially chilled mixture is removed from the chiller 1 by means of line 7 and introduced into chiller

8. In chiller 8 the distillate is chilled relatively slowly through an intermediate cooling range. If propane is allowed to evaporate the same is removed by means of line 9. After chilling through the intermediate cooling range, the propane chilled mixture is then withdrawn by means of line 10 and introduced into a third chilling stage 11. In chiller 11 the mixture is rapidly cooled to the dewaxing temperature. If propane is utilized, the same is removed by means of line 12. The chilled mixture is withdrawn by means of line 13 and passed through filter 14. The dewaxed oil and solvent are removed by means of line 15 and the wax cake by means of line 16.

The process of the present invention may be varied widely. It is to be understood that any suitable solvent, as for example, ketones, chlorinated hydrocarbons, higher esters of acetic acid, various mixed solvents such as benzol-methyl ethyl ketone, carbon tetrachloride-ethylene dichloride, and the like may be employed. Although the present invention is particularly adapted for use in solvent dewaxing operations, it may be utilized in the dewaxing of relatively wide cut distillates employing no dewaxing solvents. The filtering operation may be conducted in one or more stages. It is also within the scope of the present invention to employ solvent washing for diluting the incoming waxy stock charge, as for example in those dewaxing processes where all the fresh solvent required in the process is used first as wash solvent and the wash solution is collected separately and recycled to the incoming waxy charge for dilution

mass from the complete miscibility temperature of about 150° F. to about 90° F. in less than one minute by means of flash cooling. In general, the mass should be chilled from the complete miscibility temperature to about 90° F. in less than about three minutes. The rate of chilling in the intermediate stage should be less than about 3° per minute, preferably not over 2° per minute. The chilling in the final stage, as in 10. the initial stage, may be conducted to secure as rapid a rate as economically desirable. Desirable results are secured when the chilling in the range from about 150° F. to 90° F. is of the order of 20° per minute and when the chilling rate in 15. the range from about 35° F. to the dewaxing temperature is in excess of 5° per minute.

In order to further illustrate the invention, the following example is given which should not be construed as limiting the invention in any manner whatsoever.

Example

An intermediate lubricating oil distillate having a viscosity of 74 seconds at 210° F. was dewaxed in the following manner. One and one-half volumes of methyl normal butyl ketone were added to one volume of oil and the mixture heated to a temperature of 120° F. Various operations were conducted, chilling the mixture 30 at different rates over various cooling ranges to dewaxing temperatures in the range from 12° to 15° F. The solidification points secured on the waxes were in the range from 11° to 13° F. The results of these operations may be summarized as follows:

TABLE 1

Effect of the rate of chilling on the dewaxed oil throughout

Stock: Intermediate motor distillate 74 Say. visc. at 210° F.
Solvent: Methyl n-butyl ketone, dilution 1.5:1.0, suction 14 inches of mercury.

Operation No.	Chilling rate				Yield of dewaxed oil, percent	Total time units for chilling	Filtering rate vol./hr./sq. ft.	Capacity, using 100%, based on present process						
	Chilling rate in the temperature range							Chillers	Filters					
1.....	Controlled chilling 1° F./min.....				93	108	5.9	29.6	115.0					
	Controlled chilling 3° F./min.....													
	Shock chilling.....													
4.....	Chilling rate in the temperature range				91	36	2.6	88.8	51.0					
	120-90° F.	90-50° F.	50-35° F.	35-12° F.										
	1° F./min.	1° F./min.	3° F./min.	3° F./min.										
	2° F./min.	2° F./min.	2° F./min.	Shock ch.										
5.....	Shock ch.	2° F./min.	2° F./min.	2° F./min.	85	2.2	4.7	100.0	43.2					
6.....	1° F./min.	1° F./min.	3° F./min.	3° F./min.	92	83	4.1	38.6	80.4					
	2° F./min.	2° F./min.	2° F./min.	Shock ch.										
	Shock ch.	2° F./min.	2° F./min.	Shock ch.										

purposes. The ranges of the respective cooling stages will, of course, depend upon the particular lube distillate being dewaxed, the solvent or solvent mixture being employed, as well as upon the type of waxy constituents present. It is to be understood that some overlapping will occur. However, in general, the initial cooling stage is from the complete miscibility temperature to a temperature of about 80° to 90° F. The intermediate cooling stage is over the range from about 30° or 90° F. to 30° or 40° F. The final cooling stage is over the range from about 30° or 40° F. to the dewaxing temperature. The rate of chilling in the initial cooling stage may be as rapidly as economically possible when having no regard to the type of wax crystals being formed. For example, it may be desirable to cool the

60 From the above data it may be readily seen that when operating in accordance with the present process the capacity of the cooling equipment was increased by 300% and the capacity of the filters was decreased by about 13% over controlled chilling of 1° per minute over the entire range. The process of the present invention as illustrated by operation No. 6 is a distinct advantage over the process as illustrated by operations No. 1 to No. 5 inclusive. The best other operation was operation No. 2 in which the capacity of the chilling equipment was increased by about 89% with the result that the capacity of the filtering equipment was reduced to about one-half.

The present invention is not to be restricted in any manner whatsoever, but only by the fol-

lowing claims in which it is desired to claim all novelty insofar as the prior art permits.

I claim:

1. Process for removing waxy constituents from a petroleum oil waxy distillate comprising adding to said distillate about one and one-half volumes of methyl normal butyl ketone per volume of distillate, heating the mixture to a temperature of about 120° F., rapidly chilling the mixture from this temperature in an initial cooling stage to about 90° F., slowly chilling the mixture in a secondary cooling stage from about 90° F. to about 35° F., rapidly chilling the mixture in a final cooling stage from about 35° F. to about 12° F., and then filtering the chilled mass to remove the waxy constituents.

2. Process in accordance with claim 1 in which the distillate is chilled in said initial stage at the rate of about 20° per minute, is chilled in said secondary stage at the rate of about 2° per

20 minute and is chilled in said final cooling stage at the rate of about 5° per minute.

3. A method for removing waxy constituents from a petroleum oil waxy distillate which comprises adding methyl n-butyl ketone to the distillate as a dewaxing solvent, heating the mixture to a temperature of about 120° F., to obtain substantially complete miscibility of the waxy constituents and dewaxing solvent in the distillate, rapidly chilling the mixture from about 120° F. in an initial cooling stage to about 90° F. at a rate of about 20° F. per minute, slowly chilling the mixture in a secondary cooling stage from about 90° F. to about 35° F. at a rate of about 2° F. per minute, rapidly chilling the mixture in a final cooling stage from about 35° F. to about 12° F. at a rate of about 5° F. per minute, and then filtering the chilled mixture to remove the precipitated waxy constituents.

OLDRICH S. POKORNY.
